(57) **CLAIM**

The ornamental design for a monitor arm, as shown and described.

DESCRIPTION

FIG. 1 is a rear perspective view of the monitor arm embodying the new design;

FIG. 2 is a front perspective view thereof;

FIG. 3 is a left side elevation view thereof;

FIG. 4 is a right side elevation view thereof;

FIG. 5 is a rear elevation view thereof;

FIG. 6 is a front elevation view thereof;

FIG. 7 is a top plan view thereof;

FIG. 8 is a bottom plan view thereof; and,

FIG. 9 is another perspective view of the monitor arm, showing our new design with environment.

Broken lines are used to illustrate features of the monitor arm that form no part of the claimed design.

1 Claim, 9 Drawing Sheets
